UNITED STATES PATENT OFFICE.

PETER D. PAULS, OF MAYWOOD, ILLINOIS.

ART OF COOLING SUBSTANCES.

Application filed February 17, 1922. Serial No. 537,347.

To all whom it may concern:

Be it known that I, PETER D. PAULS, a citizen of the United States, residing at Maywood, in the county of Cook and State 5 of Illinois, have invented a new and useful Improvement in the Art of Cooling Substances, of which the following is a specification.

My invention relates generally to cooling 10 apparatus for cooling, more particularly, air, though it may be used for cooling other substances, it having been devised, more particularly, though not exclusively, for use in the cooling of the air in buildings such as 15 residences, churches, schools, theatres, stores and factories, either with or without ventilation thereof.

My primary objects are to provide a cooling 20 apparatus which shall be of novel, simple and economical construction and economical to operate, and which shall operate in a highly efficient manner to perform its function; to provide for the cooling of the substance to be cooled by utilizing 25 the cooling effect of evaporating moisture, and in this connection to provide for the evaporating of the moisture by subjecting it to a flowing gaseous substance, such as, and by preference, air, and to utilize to the 30 maximum degree the refrigerative effect of the gaseous substance after it has served the purpose of evaporating the moisture; to provide for the humidifying of the substance to be cooled, and regulation of the 35 degree of humidification; to provide for the accomplishment of the above-recited objects in the cooling of air for rooms; to provide, in the cooling of air as stated, for the desired ventilation of the rooms by introducing 40 into the latter the desired amount of fresh outside air, and the moistening of the air to the desired degree, either with or without the admission of fresh air, and to cleanse the air of dust.

My invention having been devised for use, 45 more particularly, as above stated, in the cooling and ventilating of rooms, such as the rooms of residences, etc., I have chosen to illustrate it as applied to this purpose, but 50 without, however, desiring to be understood as intending to limit it thereto.

Referring to the accompanying drawings: Figure 1 is a view in vertical longitudinal section of a cooling element involving my 55 invention, certain of the parts thereof being shown in elevation, the section being taken

at the line 1—1 on Fig. 2, and viewed in the direction of the arrows. Figure 2 is a plan sectional view of the structure shown in Fig. 1 with certain parts not sectioned, the section 60 being taken at the line 2—2 on Fig. 1 and viewed in the direction of the arrows. Figure 3 is a broken section taken at the line 3—3 on Fig. 2 and viewed in the direction of the arrows. Figure 4 is a section taken 65 at the line 4—4 on Fig. 2 and viewed in the direction of the arrows. Figure 5 is an enlarged broken vertical section at one of the tubes through which the air to be cooled passes and in which it is cooled, the section 70 being taken at the line 5—5 on Fig. 1 and viewed in the direction of the arrows. Figure 6 is a broken section taken at the line 6 on Fig. 2 and viewed in the direction of the arrows. Figure 7 is a broken section taken at the 75 line 7 on Fig. 2 and viewed in the direction of the arrow. Figure 8 is a face view of a blower forming a part of the structure of Figs. 1 and 2; and Figure 9, a view in vertical elevation, with certain parts in section, 80 of a cooling and ventilating system for a room of a building involving my invention and of which the apparatus shown in the preceding figures is a part.

Referring first to the cooling element detailed in Figs. 1 to 8 inclusive, this element comprises a shell, or drum, 10 having restricted inlet and outlet openings 11 and 12, respectively, at its opposite ends, to which pipes 13 and 14, respectively, are connected, 85 the upper portion of the shell being provided with a water-receiving receptacle 15 formed of the top wall 16 of the shell, upwardly-extending side and end walls 17 and 18, respectively, one side wall only being 90 shown, and the upwardly-extending stub-tubes hereinafter described. The lower wall is provided at intervals with upwardly-extending stub-tubes 20 which are open at 95 opposite ends and open at their lower ends through the bottom-wall 19, these stub-tubes being arranged in rows, with the tubes of adjacent rows staggered as shown in Fig. 2. Telescoping with the upper ends of the stub-tubes 20 are upwardly-extending tubes 21 100 located in the shell 10 and extending at their upper ends through upwardly-extending stub tubes 22 open at their opposite ends and opening at their lower ends through the top-wall 16 of the shell, the tubes 22 being arranged as explained of the stub-tubes 20 so 105 that the stub-tubes 22 will vertically align.

with the stub-tubes 20, the tubes 22 extending upwardly into the receptacle 15 and being of such diameter that an annular space 23 will be presented between each tube 21 and the stub-tube 22 extending through it. Preferably, and in accordance with the particular illustrated embodiment of my invention, the tubes 21 are surrounded by tubular sheathings 24 of moisture-absorbing material, such as felt, which extend upwardly through the spaces 23 and fit the tubes 21 as snugly as practicable possible, and are turned outwardly over the upper edges of the stub-tubes 22 as shown to present the depending portions 25 which extend into water provided in the receptacle 15 as hereinafter described for the purpose of maintaining the sheathings 24 in moistened condition, the sheathings operating as wicks to absorb water from the receptacle 15 and by capillary attraction disseminate it throughout their extents. There is thus provided a series of conduits for the passage therethrough of the air to be cooled, which extend through the shell and present a media for exposing moisture to the flow of air supplied to the shell 10 and passed therethrough, whereby the air in passing through the conduits is cooled by the absorption of heat therefrom in the evaporating of the moisture. A blower 26 is shown as located adjacent the outlet 12 for effecting the desired flow of air through the shell 10.

The means shown for maintaining a supply of water in the receptacle 15 comprise a pipe 27 which leads from any desirable source of water under pressure and opens into the receptacle 15, wherein its outlet is provided with a float-controlled valve 28 of any desirable construction, whereby water to a level, as indicated by the dotted line 129, and extending above the lower ends of the portions 25 of the sheathings, is maintained in the receptacle 15.

The apparatus shown also comprises means for quickly saturating the sheathings 24 in the beginning of the operation of the apparatus, these means comprising a horizontal series of pipes 29 arranged parallel with each other and extending crosswise of the shell 12 and alternating with the several rows of pipes 21, these pipes 29 containing perforations 30 in their sides. The pipes 29 at one side of the shell 10 are journaled at their open extremities in openings 31 in the wall of a pipe 32 in the shell and extending lengthwise thereof and supported on brackets 33 secured to the inner surface of the shell-wall, these ends of the pipes 29 being provided with arms 34 extending at an angle thereto and pivoted at their upper ends, as represented at 35, to a horizontal bar 36 which extends at one end through an end wall of the shell 10 at which it is pivotally connected, as represented at 37, to a link

38 pivoted at 39 to an operating lever 40 pivoted at 41 on the pipe 14, the connection of the link 38 with the lever 40 being between the ends of the latter. The ends of the pipes 29 at the opposite side of the shell 10 are closed and journaled in openings in a horizontally extending bar 42 supported by brackets 43 secured to the inner surface of this side of the shell 10, the pipes 29 being held against lengthwise movement in either direction by the arms 34 at one end thereof and by collars 29^a provided at the opposite end.

It will be understood from the foregoing that by means of the lever 40 the pipes 29 may be rocked on their journals in both directions, thereby spraying upon the sheathings throughout their height, water supplied through the pipe 32 from any suitable source, to thoroughly saturate the sheathings, and after the latter are moistened as stated the supply of moisture to the sheathings is effected by absorption of water from the receptacle 15. In the use particularly of hard water, the continued evaporation thereof on the sheathings 24 results in the deposition therein of salts in the water which, if not removed, results in impairing the sheathings for the most effective functioning, and to provide for the ready removal of the deposited salts I provide for washing them away, the means shown for this purpose comprising a pipe 44, having a manually-operated valve 45, leading from any suitable source of water supply, the inner end of this pipe opening into the receptacle 15 and being equipped with a float-controlled valve 46, the valve 46 being so disposed that when water is supplied to the pipe 44 it will permit water to flow into the receptacle up to a level above the tops of the tubes 22 and the sheathings 24 but below the upper extremities of the tubes 21. When it is desired to flush the sheathings 24, the valve 45 is opened and a head of water thus applied to the sheathings 24 which operates to wash out of the latter the deposited salts referred to, the water draining from the shell 10 through the outlet pipe 47.

Referring to the arrangement shown in Fig. 9 and in which the cooling element described is incorporated, a room to be cooled and ventilated is represented at 48, it being shown as provided with an inlet 49 and an outlet 50 for air, connected respectively with air-ducts 51 and 52. The air-duct 51, which has a fan 53 interposed therein, connects with a chamber 54 into which the lower ends of the stub-tubes 20 open, the duct 52 communicating between its ends with a pipe 55, having a damper 56, and opening into the top of a chamber 57 surmounting a shell 58 having an inlet 59 and an outlet 60 and containing a bank of cross-pipes 61 out of communication with the interior of the shell 125 130

58 and opening at their upper ends into the chamber 57 and at their lower ends into the receptacle 15 which latter is otherwise closed at its upper end, the chamber containing any suitable construction of air-screening means as for example those shown and comprising a diaphragm 62 of fabric disposed about supporting rods 63 to extend in zigzag condition and through which the air in passing 10 downwardly through the chamber 57 is obliged to pass. The lower end of the duct 52, which contains a damper 52^a, opens into a pipe 64 one end of which terminates in a chamber 64^a open to the atmosphere and 15 containing air-screening means represented at 65 shown as of the same construction as the air-screening means in the chamber 57, and the other end of which opens into a chamber 66 communicating with a bank of 20 pipes 67 located in a shell 68 and opening at their lower ends into a chamber 68^a communicating with the pipe 13, the interiors of the pipes 67 being out of communication with the shell 68 and the latter having an 25 inlet 69 communicating with the pipe 60 and an outlet 70 communicating with a pipe 71. The pipe 14 communicates with the inlet 59 of the shell 58, this pipe also connecting, by a pipe 72, with the pipe 51 between the fan 53 and the chamber 54, the pipe 72 containing a damper 72^a. A pipe 30 73 opens at one end into the top of chamber 57 and at its opposite end terminates in a chamber 74 which is open to the atmosphere and 35 contains air-screening means represented at 75 and shown as of the same construction as those located in chamber 57, the pipe 73 containing a damper 73^a.

In the operation of the described system, 40 assuming that it is desired to cool the air for circulation through the room 48 without supplying fresh outside air, the damper 73^a is closed, and the air from the room 48 is caused to circulate by the fan 53, through a 45 closed course comprising the room 48, duct 52, chamber 57, pipes 61, receptacle 15, pipes 21 and 20, chamber 54 and pipe 51. Air from the outside is caused, by the operation of the fan 26, to be drawn into the pipe 50 64 through the chamber 64^a, thence into the chamber 66, through pipes 67, chamber 68^a, pipe 13 and shell 10, and forced from the latter through the pipe 14, shell 58, pipe 60, shell 68 and out through pipe 71. The air 55 for evaporating the moisture on the sheathings 24 in the shell 10 is thus caused to traverse, before entering this shell, the tubes 67 wherein it is subjected to the relatively cool air passing through the shell 68 whereby the air for evaporating the moisture as stated is pre-cooled, and after it has passed through the shell 10 and therein effected the evaporation of the moisture for the cooling purpose, it is passed through the 60 shell 58 wherein it operates to cool the pipes 65

61 and consequently the air drawn from the room 48 and in its passage to the main cooler of which the shell 10 is a part. Thus, by the arrangement shown, the cooling effect of the air after leaving the shell 10, is utilized to 70 the maximum degree in the cooling of the air for introduction into the room 48, whereby the maximum cooling effects are obtainable by an apparatus of a given size.

When it is desired that the air withdrawn 75 from the room 48 be replaced by fresh air, the damper 73^a is opened and the damper 52^a also opened, and damper 56 closed, whereby at least a portion of the air employed for evaporating the moisture in the shell 10 is taken from the room 48 through the duct 52 and the air to be cooled into the chambers 58 and 10 and thence to be forced into the room 48 through the duct 51, is taken in wholly through the pipe 73, thereby not only effecting ventilation of the room 48 but also supplying air in cooled condition thereto.

It is sometimes desirable, as for example where the atmosphere is comparatively dry, 90 to moisten the air discharged into the space 48, to cause it to present a greater degree of humidity than the atmosphere, and to this end the damper-equipped passage 72 connecting the pipe 14 and the pipe 51 is 95 provided. To increase the humidity of the air discharged into the space 48, the damper 72^a is opened to a degree depending upon the amount of humidity desired, the opening of this damper permitting of the passage 100 from the shell 10 of a part of the air discharging from the shell 10 in moist condition, into the pipe 51 wherein it commingles with the air which has been cooled by passing through the conduits 21 and then 105 passes into the space 48.

In order to avoid clogging of the pipe 51, by the accumulation of water therein condensing in the pipes 21 where the air discharging therethrough contains moisture, I 110 provide a valve-equipped draw-off pipe 100 communicating with the pipe 51.

While I have illustrated and described a particular construction of apparatus for practicing my improved method, I do not 115 wish to be understood as intending to limit my invention to the use of such apparatus. Furthermore as regards my invention, in so far as it relates to apparatus, I do not wish to be understood as intending to limit it to 120 the particular construction shown nor to its use for the particular illustrated purpose, as the apparatus may be variously modified and altered, and employed for other purposes than the particular one shown, without departing from the spirit of my invention.

What I claim as new, and desire to secure by Letters Patent, is:

1. In cooling apparatus, the combination 130

4
of a conduit for the passage therethrough of a substance to be cooled, means for causing air to flow into contact with moisture for cooling the substance by the evaporation 5 of said moisture, and means for causing the air after it has been cooled by contact with the moisture, to exert a cooling effect on the substance before the subjection of the latter to the cooling effect of the evaporating 10 moisture.

2. In cooling apparatus, the combination of a conduit for the passage therethrough of a substance to be cooled, means for causing air to flow into contact with moisture 15 for cooling the substance by the evaporation of said moisture, and means for causing the air after it has been cooled by contact with the moisture, to exert a cooling effect on the substance before the subjection of the 20 latter to the cooling effect of the evaporating moisture and on the air before the latter contacts with the moisture.

3. Cooling apparatus comprising a shell having an inlet and an outlet, a series of 25 stub-tubes opening at their lower ends through the lower wall of said shell and at their upper ends into the interior of said shell, a second series of stub-tubes opening at their lower ends into said shell through 30 the upper wall thereof and open at their upper ends, pipes located within said shell and extending at their upper ends in the stub-tubes of the said second series thereof, said first-referred-to stub tubes and the lower 35 ends of said tubes having telescoped relation, and moisture-absorbing material located at the exterior surfaces of said tubes.

4. Cooling apparatus comprising a shell having an inlet and an outlet, a series of 40 stub-tubes opening at their lower ends through the lower wall of said shell and at their upper ends into the interior of said shell, a second series of stub-tubes opening at their lower ends into said shell through 45 the upper wall thereof and open at their upper ends, pipes located within said shell and extending at their upper ends in the stub-tubes of the said second series thereof, said first-referred-to stub-tubes and the 50 lower ends of said tubes having telescoped relation, moisture-absorbing material located at the exterior surfaces of said tubes, and a receptacle for liquid into which said second series of stub-tubes extend.

5. The combination with a room to be 55 cooled, of means for effecting a flow of air into the room, means for subjecting the air before its introduction into the room, to the cooling effect of water evaporated by air flowing in contact therewith, and means for 60 preliminarily cooling the air for introduction into the room, by subjecting it to the cooling effect of the air employed for evaporating the water.

6. The combination with a room to be

cooled, of means for effecting a flow of air into the room, means for subjecting the air before its introduction into the room, to the cooling effect of water evaporated by air flowing in contact therewith, and means 70 whereby air after contacting with the water to evaporate it, is caused to flow into the room.

7. The combination with a room to be 75 cooled, of means for effecting a flow of air into the room, means for subjecting the air before its introduction into the room, to the cooling effect of water evaporated by air flowing in contact therewith, and means whereby air after contacting with the water 80 to evaporate it, is caused to flow into the room, said last-named means being adjustable to vary the flow of moist air into the room.

8. The method of cooling a substance 85 which consists in subjecting the substance to the cooling action of liquid evaporated by contact with air and preliminarily cooling the substance by subjecting it to the cooling effect of the air after contacting the latter 90 with the liquid.

9. The method of cooling a substance which consists in subjecting the substance to the cooling action of water evaporated by 95 contact with air and preliminarily cooling the substance by contacting it with the air after contacting the latter with the liquid.

10. The method of cooling a substance which consists in subjecting the substance to the cooling action of liquid evaporated by 100 contact with air and preliminarily cooling the substance and cooling the air preliminary to its contact with the liquid, by subjecting the substance and the air to the cooling effect of the air after contacting the 105 latter with the liquid.

11. The method of cooling a substance which consists in passing the substance through a conduit and subjecting the substance to the cooling action of liquid evaporated by 110 contact with air and preliminarily cooling the substance and cooling the air preliminary to its contact with the liquid, by subjecting the substance and the air to the cooling effect of the air after contacting the 115 latter with the liquid.

12. The method of cooling a room which consists in subjecting the air, to be introduced into the room, to the cooling action of liquid evaporated by contact with air and 120 preliminarily cooling the air, for introduction into the room, by subjecting it to the cooling effect of the air, employed for evaporating the liquid, and after contacting it with the liquid.

13. The method of cooling a room which consists in subjecting the air, for introduction into the room, to the cooling action of water evaporated by contact with air and 125 preliminarily cooling the air, for introduc-

tion into the room, by contacting it with the air employed for evaporating the liquid, and after contacting it with the liquid.

14. The method of cooling a room, which consists in subjecting the air, for introduction into the room, to the cooling action of liquid evaporated by contact with air and preliminarily cooling the air, for introduction into the room, and cooling the air employed for evaporating the liquid and before contacting with the liquid, by subjecting the air for both purposes to the cooling effect

of the air, employed for evaporating the liquid, after contacting this air with the liquid.

15. The method of cooling and humidifying a substance which consists in cooling the substance by subjecting it to the cooling effect of liquid evaporated by a flowing current of air and commingling with the substance thus cooled a portion, at least, of the air moistened by the evaporation of the liquid.

PETER D. PAULS.
